UNITED STATES PATENT OFFICE.

CHARLES W. PALMER, OF SANDPOINT, IDAHO.

VALVE-SPRING LIFTER.

1,301,733.

Specification of Letters Patent. Patented Apr. 22, 1919.

Application filed May 1, 1918. Serial No. 231,366.

To all whom it may concern:

Be it known that I, CHARLES W. PALMER, a citizen of the United States, residing at Sandpoint, in the county of Kootenai and State of Idaho, have invented new and useful Improvements in Valve-Spring Lifters, of which the following is a specification.

The present invention relates to improvements in tools or implements of the class having jaws which are relatively movable to operate upon the part or parts engaged therewith, and the primary object of the invention is to provide a novel and improved tool of this character which is particularly adapted for use in lifting the springs such as used upon the valves of internal combustion engines, to enable the springs to be detached from the valve stems preparatory to the removal of the valves, the tool provided for this purpose by the present invention acting to lift the spring easily and to hold the spring securely in lifted position, whereby the valve may be removed with facility, and the jaws of the tool are forked and provided with means for varying the distance between the forks of each jaw, thus enabling the tool to be adjusted to accommodate it to dimensions of the valve stem, spring seat collar, or the spring retaining means, and also to the valve lifter or other part against which the tool rests.

Other objects of the invention are to provide a tool which is adapted to serve not only as a valve spring lifter but which may also be used as a vise or clamp to grip and hold parts upon which work is to be performed and to hold the head of a bolt against turning while the nut is tightened thereon.

To these and other ends, the invention consists in certain improvements, and combinations and arrangements of parts, all as will be hereinafter more fully described, the novel features being pointed out particularly in the claims at the end of the specification.

In the accompanying drawings:

Figure 1 is a side elevation of a tool or implement constructed in accordance with the present invention, showing the tool or implement in use for the lifting of a valve spring;

Fig. 2 is a top plan view of the tool.

Fig. 3 is a side elevation of the tool, showing the jaws thereof in close relation;

Fig. 4 is a side elevation of a portion of the tool showing the operating screw provided with a hand-wheel or grip for rotating it, and Fig. 5 is a side elevation of a portion of the tool showing the manner in which the jaws thereof are formed.

Similar parts are designated by the same reference characters in the several views.

Tools or implements constructed in accordance with the present invention are capable of use generally by mechanics and others in various instances where it is necessary to relatively separate or spread apart mechanical devices of various kinds and also where it is desirable to clamp or hold parts while being manipulated or worked upon. The tool is especially adapted to fulfil the requirements of lifting the springs of valves of internal combustion engines preparatory to the removal of the valves, although it is also capable of efficient use for the purposes to be hereinafter described. It is to be understood that the invention is not restricted to the precise construction shown, as equivalent constructions are contemplated and will be included within the scope of the claims.

The tool comprises a pair of jaws 1 and 2, the operative portions of these jaws being forked, and means is provided for moving the jaws toward and from one another and for maintaining the jaws in parallelism at all adjustments thereof. Preferably, and as shown, each jaw comprises a strip of steel or other suitable metal which, as shown in Fig. 5 is doubled intermediately to bring the two ends of the strip into substantial parallelism, thus forming arms the extremities of which are spaced laterally and constitute prongs 3 of a fork. Means is provided for varying the distance between the prongs on each jaw, such means comprising a nut 4 which is rotatably fitted to the inner side of one arm of the jaw and a screw 5 which is fixed to the inner side of the other arm of the jaw, the nut engaging the screw and being rotatable by a wrench to cause the forks of the jaw to spread or contract according to the dimension of the part to be straddled by the fork. The jaws are shifted in a direction toward and from one another by a screw 6 which engages a threaded nut or block 7 secured to one of the jaws, the jaw 2 in the present instance, and it is shouldered and rotatably fitted in a bearing block 8 secured to the other jaw, the

jaw 1 in the present instance. Either a hand wheel or a ratchet handle may be provided for rotating the screw to shift the jaws in either direction, the screw being shown in Fig. 4 as provided with a hand wheel 6; while in Figs. 2 and 3 a toothed wheel 9 is fixed thereon, a handle 10 being rotatable about the upper end of the screw, the handle carrying a double-armed pawl 11 which is pivoted to the handle at 12. Either arm of the pawl may be set to engage the toothed wheel, and successive swings of the handle will cause the screw to be rotated in the appropriate direction. Means is provided for maintaining parallelism between the jaws, a pair of links 13 and 14 being provided at each side of the jaws for this purpose. The links 13 are pivoted to the jaw 1 at the points 15 while the links 14 are pivoted to the jaw 2 at the points 16. The opposite ends of the links 13 and 14 carry pins 17 and 18 which are slidable in longitudinal slots 19 and 20 formed in the respective jaws. The jaws are also preferably provided with teeth or serrations 21 which may be utilized to grip a rod or other part of small diameter, as indicated by the dotted circle 22.

In using the tool as a valve lifter, the distance between the forks of one of the jaws is adjusted to enable this jaw to straddle the valve lifter or the valve lifter guide which surrounds or is adjacent to the valve lifter, and the distance between the forks of the other jaw is adjusted to enable this second jaw to straddle the valve stem or the removable spring retaining device which connects the spring with the valve stem. As shown in Fig. 1, a split collar or washer 23 is generally used to connect the spring to the valve stem, and in such cases the forks of the upper jaw will be adjusted to straddle this split collar or washer. The tool when so adjusted is introduced into a position beneath the spring seat collar 24, the upper jaw engaging the under side of this collar and the lower jaw engaging the guide 25 which surrounds the valve lifter, or some other suitable part adjacent to the lifter. While the tool is in this position, the screw 6 is operated by swinging the handle 10, the screw being rotated in a direction to separate the jaws, and this separation of the jaws causes the spring seat washer 24 to be lifted above the retaining collar or washer 23 and the latter may then be easily detached from the valve stem. The valve may then be removed in the usual way.

The tool may be used as a vise to clamp rods or other parts of relatively small dimensions by introducing such rod or part between the serrated portions 21 of the jaws and bringing the jaws together or into close relation, as shown in Fig. 3. Where it is desirable to avoid biting of the jaws into the part clamped thereby, the part to be clamped

may be similarly gripped between the smooth edges of the jaws, as indicated at 26. The tool may also be used for holding the heads of bolts while the nuts are being applied thereto by adjusting the distance between the forks of one of the jaws to enable the forks of this jaw to fit the flat sides of the bolt head and by bringing the jaws together so that the serrated portion 21 will grip the frame or some other stationary part of the structure to which the bolt is applied.

The present invention provides a tool which is especially adapted to overcome the difficulties ordinarily experienced in removing the valves of internal combustion engines, the maintenance of the jaws in parallelism during the lifting of the spring avoiding deflection of either the tool or the spring which is liable to occur where the jaws converge or diverge or are subject to lateral tilting, and, hence, the spring will be lifted with certainty, it will be held securely in lifted position, and the collar or other device which connects the valve stem to the spring may be removed easily and quickly. The ratchet screw device for operating the jaws to lift the spring also may be actuated easily, although, as is frequently the case, the tool is placed in a difficultly accessible position. The means provided by the present invention for adjusting the distance between the forks of each jaw enables each jaw to be so adjusted that the respective jaws will properly straddle the valve lifter or its guide and the valve stem and the spring attaching device connected thereto, thus insuring firm seats for the tool and the spring and preventing upsetting of either the tool or the spring seat collar. By locating the jaw-operating screw and its actuating ratchet at the end of the tool remote from the operative portions of the jaws, obstruction to the necessary manipulation of the ratchet or screw is avoided, as these parts, when the tool is applied to the spring to be lifted, will be sufficiently distant from the side of the engine to enable the ratchet to be manipulated without obstruction by the side of the engine or parts adjacent to or carried by the engine.

The present invention also presents the advantage that the tool is also capable of many other uses that will suggest themselves to skilled mechanics, its uses as a vise or clamp and as a means for holding bolts from turning being mentioned as examples.

I claim as my invention:

1. A tool for lifting the valve springs of internal combustion engines, comprising a pair of jaws having ends adapted respectively to cooperate with the spring and with a support on the engine, a screw located toward the opposite ends of the jaws and connecting them for moving said jaws apart to lift the spring, and means for maintaining

parallelism between the jaws during relative movement between them.

2. A tool of the character described comprising a pair of jaws capable of relatively moving in a direction toward and from one another, parallel motion links for maintaining parallelism between the jaws during such movement, and means for relatively moving the jaws embodying a screw operatively connecting the jaws, a screw actuating handle, and a reversible ratchet for connecting the handle to the screw.

3. A tool of the character described comprising a pair of jaws, each jaw embodying a strip of material doubled intermediately to form a pair of arms providing an operative fork at one end of the jaw, links connected to the outer sides of the arms of each jaw to maintain parallelism between the jaws, and means located between the arms of the respective jaws and operatively connected thereto to move the jaws in a direction toward and from one another.

4. A tool of the character described comprising a pair of coöperative jaws, one of said jaws being composed of a strip of material doubled to form the prongs of a fork at its extremities, means for varying the lateral distance between the prongs of the fork, and

means for relatively moving the jaws in a direction toward and from one another.

5. A tool of the character described comprising a pair of coöperative jaws, each jaw embodying a strip of material doubled intermediately to form a pair of arms providing a fork at the operative end of the jaw, and means for relatively moving said arms in a direction toward and from one another to vary the lateral distance between the prongs of the fork, and means for relatively moving the jaws in a direction toward and from one another.

6. A tool of the character described comprising a pair of coöperative jaws having means for relatively moving them in a direction toward and from one another, each jaw embodying a pair of laterally spaced arms forming a fork at the operative end of the jaw, and a screw operative between said arms to vary the distance laterally between them.

In testimony whereof I have hereunto set my hand in presence of two subscribing witnesses.

CHARLES W. PALMER.
